(57) **CLAIM**

The ornamental design for a song bird planter/feeder, as shown and described.

DESCRIPTION

FIG. 1 Is a top plan view of our song bird planter/feeder;
FIG. 2 Is a bottom plan view thereof;

FIG. 3 Is a right side elevational thereof with the left side elevational view being a mirror image thereof;

FIG. 4 Is a front elevational view thereof; and,

FIG. 5 Is a rear elevational view thereof.

The broken lines shown in the figures are for illustrative purposes only and form no part of the claimed design.
